JACQUES LAURENT, OF NEW YORK, N. Y.

Letters Patent No. 97,527, dated December 7, 1869.

IMPROVED MACHINE FOR DRILLING AND PREPARING WATCH-CASES FOR SPRINGING.

The Schedule referred to in these Letters Patent and making part of the same.

To all whom it may concern:

Be it known that I, JACQUES LAURENT, of the city, county, and State of New York, have invented a new and useful Improvement in Machinery for Preparing Watch-Cases for Springing, of which the following is a full, clear, and exact description, reference being had to the accompanying drawing, forming part of this specification, and in which—

Figure 1 represents a front view of a machine constructed in accordance with my improvement;

Figure 2, a sectional elevation of the same, taken as indicated by the line *x x* in fig. 1; and

Figure 3, a plan of said machine.

Figure 4 is a face view of a watch-case with its springs in place, in illustration of the work accomplished by the machine.

Similar letters of reference indicate corresponding parts.

The object of this invention is partly to expedite the preparation of watch-cases for the reception and attachment of their springs, but mainly to provide for an interchange of work, by insuring a uniformity, in the preparation for springing, of any number of cases, whereby not only is the getting up of a quantity of work expedited, by allowing of the taking from a heap or number of springs, any one spring to fit any one of a number of cases, but whereby great facility is afforded for renewing the springs in a watch-case when required.

The invention consists in a combination of adjustable devices in the one machine, for preparing the case for springing, so that said work, which has heretofore been done in detail or separately, may be done at one and the same time, whereby the most perfect uniformity for any number of cases is insured, and labor and time economized; and the invention includes certain combinations of parts in said machine, for insuring both independent and collective adjustment of the tools for performing the different portions of the work, to suit a variety of different-sized cases, or different relative arrangements of the springs; also, adjustable means for burring out the case for the nose of the catch-spring to work in.

Referring to the accompanying drawing—

A represents the frame of the machine, and B the bed, by which the watch-case to be prepared for springing is carried, said case, C, being placed within, and held from moving by a die, D, secured to the bed, and of which there may be any desired number, to suit different styles and sizes of cases.

This bed B is adjustable horizontally, by a screw, *a*, on a table, E, which, in its turn, is adjustable vertically by a lever, *b*. These adjustments are for the purpose of setting the work in proper relation to the several tools, and for forcing it up to the latter, under regulation of an adjustable stop, *c*.

F and F' are drills for making the holes for the screws *d* and *d'*, which serve to attach the hinge and catch-springs *e* and *f* to the case; and

G is a drill for making or locating the hole *h*, through which the nose of the hinge-spring plays. This hole, after being drilled, is filed out, or dressed to the proper shape.

H is a revolving burr, for forming or dressing the recess *i*, within which the nose of the catch-spring *f* plays.

The drills F, F', and G, are rotated or driven by means of bands applied to pulleys *k* and *l*, secured to the tops of the drill-holders *m* and *n*, which are free to rotate within or through hollow screws, I, I', and J, made to project through and fit sliding boxes K, K', and L, by which means said drills may be independently raised or lowered, to suit different work, and be adjusted horizontally, as required.

Thus, while the several drills are adjustable vertically by turning the hollow or screw-sockets I, I', and J, the boxes K, K', and L, to said screws, are adjustable horizontally, by means of screws M and N, suitable slots, *o*, *o'*, and *p*, being made in the upper plate of the main frame, to provide for such horizontal adjustments, the one of which, namely, that regulating the drill G, is at right angles to those regulating the drills F F', which latter drills are unitedly adjustable in reverse horizontal directions, by the one screw M, to insure their proper relation to each other, and to different diameters of watch-case, said screw M having right and left-hand threads cut upon it, to effect such double adjustment.

The several drills having been thus suitably adjusted, and bed properly set, the holes for the screws *d* and *d'* and hole *h*, for the nose of the hinge-spring, may all be drilled at one and the same time, and perfect uniformity insured in operating upon a number of cases in succession, which facilitates interchanging of the cases and springs, and expedites the performance of the work, as hereinbefore referred to.

The specified adjustments of the drills, taken in connection with the horizontal adjustment of the bed B, and its lift of the work in feeding, till arrested by the stop *c*, adapts the machine to all styles and sizes of work.

Simultaneously, also, with the formation of the hole *h* and holes for the screws *d* and *d'*, and by the same operation of lifting the bed and table by the lever *b*, the watch-case has its recess, *i*, for play of the nose of the catch-spring, cut or dressed in it by the rotation of the burr H, that is carried by a horizontal shaft, P, driven by a pulley, *r*, and working in screw centres, *s*, which are carried by a hanger, Q.

This hanger Q is adjustable, on slackening a locking-nut, *u*, along a slot in the top plate of the main frame, in a direction which is at right angles to the axis of

the shaft P, that may be adjusted longitudinally by the screw centres s s. In this way, every provision is made for varying the position of the burr to suit different sizes of watch-cases, and to secure uniformity throughout a series of them, in accordance with the holes made by the drills F, F', and G, for effecting interchange of the cases and springs.

What is here claimed, and desired to be secured by Letters Patent, is—

1. The combination of the drills F F', their holders m m, drill-stocks I I', and sliding boxes K K', with the right and left-handed adjusting-screw M, substantially as specified.

2. The combination of the drill G, its holder n, the drill-stock J, and horizontal adjusting-screw N, with

the adjustable drills F F', and their holders m m, essentially as herein set forth.

3. The combination of the adjustable revolving burr H with the adjustable drills F, F', and G, and their holders, substantially as specified.

4. The combination of the vertically and horizontally-adjustable drills F, F', and G, and their holders, the adjustable rotating burr H, and the horizontally-adjustable bed B, made capable of vertical action, and carrying a suitable die, D, essentially as and for the purpose or purposes herein set forth.

JACQUES LAURENT.
